Attorney

UNITED STATES PATENT OFFICE.

EDWARD ROBARDS, OF STILESVILLE, INDIANA.

FENCE-POST.

SPECIFICATION forming part of Letters Patent No. 367,848, dated August 9, 1887.

Application filed November 29, 1886. Serial No. 220,773. (No model.)

To all whom it may concern:

Be it known that I, EDWARD ROBARDS, a citizen of the United States, residing at Stilesville, in the county of Hendricks and State of Indiana, have invented certain new and useful Improvements in Fence-Posts; and I do hereby declare that the following is a full, clear, and exact description of the invention, which will enable others skilled in the art to which it

15 appertains to make and use the same.

My invention relates to fence-posts; and the object of the invention is to provide improved means for holding the post in the ground when once placed in position, and to provide improved means for retaining the wires of the fence in position.

A further object of the invention is to provide a fence-post which shall be simple in its construction, cheap to manufacture, and 20 strong and durable.

Fence posts of this class have heretofore been constructed with a tubular metallic body having a closed tapering lower end, said end being threaded and adapted to be screwed into the ground. Similar posts have also been 25 constructed in which V-shaped notches for retaining the wire are provided at the junction of the wings forming the body of the post, the wings converging at their lower ends to 30 form a vertical slot, in which is pivoted a dependent plate having longitudinal laterally-projecting flanges.

My invention is designed as an improvement over these prior constructions; and to 35 this end it consists in the improved construction and arrangement of parts, as hereinafter fully described, and particularly pointed out in the claim.

In the drawings, Figure 1 is a perspective view of a fence-post embodying my invention. Fig. 2 is a vertical section of the same. Fig. 3 is a horizontal section; and Fig. 4 is a detail view of the sleeve carrying the flange and bent strip, said sleeve being removed.

40 Corresponding parts in the several figures are denoted by the same letters of reference.

Referring to the drawings, A represents the body of the post, which consists of a long tubular portion, B, of metal, which tubular portion is provided at suitable intervals with ap-

proximately V-shaped slits or slots, as shown, which are adapted to receive the wires. When the wires are to be inserted in the slits, they are pressed or forced down below the projections b, formed by the V-shaped slots, and the 55 wires inserted. As soon as released they occupy a position at the upper ends of the V-shaped slots, so that all possibility of their detachment is prevented.

At the lower end of the body portion is located a shank or sleeve, C, which may or may not be solid, as desired, said shank or sleeve fitting within the main or body portion B, and held therein by a transverse pin, c, which passes through the body portion and the shank 60 or sleeve. Depending from the shank or sleeve is a blade or flange, which is sharpened at its lower end, so that it will readily enter the ground.

D represents a metallic strip or cross piece, 70 which is secured in any preferable way to the blade or flange, said cross-piece being bent or twisted at its ends, as shown, and adapted to steady the post, and also serve to hold it in the ground and prevent its too easy removal. 75

A fence-post constructed as above described is simple, cheap, and durable, and by its use the wires may be readily and quickly strung or unstrung, and at the same time will be held securely in position.

Having thus described my invention, what I claim is—

The combination, in a fence-post, with the tubular body having an open cylindrical lower end, of the cylindrical sleeve corresponding to 85 and inclosed within the lower end of the tubular body, a transverse securing-pin passing through the body and sleeve, the blade or flange depending from the sleeve and having a portion projecting within the same, and the 90 transverse blade secured to the face of the flange and having each end twisted, as set forth.

In testimony whereof I affix my signature in presence of two witnesses.

EDWARD ROBARDS.
